UNITED STATES PATENT OFFICE.

WILLIAM S. EATON, OF SAG HARBOR, NEW YORK.

PLATE-PRINTING AND EMBOSSED MACHINE.

SPECIFICATION forming part of Letters Patent No. 752,052, dated February 16, 1904.

Application filed April 30, 1903. Serial No. 154,934. (No model.)

To all whom it may concern:

Be it known that I, WILLIAM SYLVESTER EATON, a citizen of the United States of America, and a resident of Sag Harbor, in the county of Suffolk and State of New York, have invented certain new and useful Improvements in Plate-Printing and Embossing Machines, of which the following is a specification.

This invention relates to plate-printing and embossing machines; and it comprises in brief means in conjunction with the oscillatory rocking movement of the die-plate bed, whereby such movement causes the ink-wiping devices to be actuated in the performance of their functions, the inking-roller to be carried to and from its source of supply and to the die-plate and the inking-roller to avoid contact with the opposite surface edges of the impression or die-plate in the passage to and from of the latter beneath said roller.

The invention further includes the combinations of parts and novel arrangements thereof permitting the die-plate to be in full view of the operator at all times excepting momentarily when the actual impressing is taking place, as well as such further combinations and arrangements of parts as will be fully described hereinafter, and particularly pointed out in the claims.

In the drawings accompanying this application, Figure 1 is a side elevation of my improved machine, showing the die-plate bed and matrix-support extended apart on their joint-pivot, the die-plate being in process of passing beneath the inking and wiping rollers. Fig. 2 is a similar view, but showing the die-plate bed and matrix-support closed together in the act of creating the impression and embossment and showing the inking-roller at this time as placed in the act of receiving a fresh quota of ink from the feed-roller in the reservoir. Fig. 3 is a plan view taken on the line X-X of Fig. 1, and Fig. 4 is a rear elevation.

As will be observed, my improvements are applied in conjunction with a press of the type wherein the bed carrying the die-plate and a support carrying the matrix and sheet to be impressed are pivotally connected by a common shaft and have crank and link connections, whereby the movement of one of said

elements is communicated to the other, providing combined advance and retreat actions, during and in consonance with which the various steps of inking, wiping, and printing, and setting and removing the sheets being impressed are accomplished.

The frame of the machine is indicated in the drawings by the numeral 1, and the opposite sides 2 2 of the bed 3 are pivotally connected with the frame by links 4 4. The inner end 60 of bed 3 is pivoted upon a shaft 5, which latter also serves as the pivotal bearing for the inner end of a frame 6, that carries the matrix-support or impression-sheet table.

7 indicates the pulley-shaft; 8, a pinion keyed 65 thereon; 9, a gear-wheel in mesh with said pinion; 10, a transverse shaft upon which said gear 9 is secured; 11, a sleeve loosely mounted upon shaft 10 and carrying arms 12 12, whose opposite ends are pivotally connected to the 70 matrix-support frame 6. A disk 13 is keyed upon the shaft 10 and has eccentrically pivoted thereto at 14 one end of a crank-arm 15, whose opposite end is pivoted upon a shaft 16 exterior to one of the sides 2 of bed 3. A corresponding crank-arm 17 is similarly pivoted to the gear-wheel 9 and mounted upon the shaft 16 at the opposite side of bed 3 to provide a uniform torque in the operation of the machine.

The shaft 16 is pivotally connected to the lower portion of the frame 1, at each side thereof, by links 18 18. The aforesaid members constitute the usual parts of this form of folding-press, whose movement is well 85 known, the weight at the lower end of the bed sides 2 2 helping to swing back the bed to the open position after each impression.

Treating first of the improved inking mechanism, 19 indicates a reservoir within which a feed-roller 20 is rotatably mounted, being driven by a pulley 21, secured upon its shaft, said pulley 21 being coupled by a pulley-cord 22 with a pulley 23, that is fast upon a shaft 24, which latter member is provided with 95 pulley 25, which is in frictional engagement with a power-shaft. (Not shown.) The die-inking roller consists of a rod 26, having a central concentric pad portion 27 and being normally supported at its ends in the adjust- 100

able bearings 109 at the lower ends of the guide-slots 28 28 in the opposite side frame. It will be noted that said slots 28 28, while vertical at their lower portion, incline 5 rearwardly at an upward angle at their opposite ends, the purpose whereof will presently appear. It will also be noted that the upper surface of the bed 3 is continued rearwardly by the curved arms or ways 29 29, 10 and it is their function with the forward oscillation of the bed 3 to support the rod 26 momentarily in the elevated position to which it has been raised with the rising inclination of the bed and likewise with the return movement. 15

A pair of bifurcated outwardly-curved fingers 30, which straddle the rod 26, are pivoted to the frame at either side, as at 31, and each of said pairs of fingers continues into a 20 pending rearwardly-curved arm 32, located in the forward path of the shaft 16, to be moved therewith, whereby when the rod 26 has been elevated beyond the vertical portion of the slots 28 28 the forward fingers of the pairs 25 30 in their rearward movement will carry the rod 26 up the rearward inclines of slots 28 28 and will deposit said rod into the depressions 33 33 in the frame, which serve as temporary bearings, while the ink-pad 27 is 30 receiving a fresh quota of ink from the feed-roller 20. The rod 26 is provided with a pinion 34, which is adapted when the pad 27 is upon feed-roller 20 to mesh with a pinion 35 upon the shaft of said feed-roller, thereby rotating said inking-roller oppositely to the rotation of the feed-roller and permitting the latter to supply it uniformly with a film of ink for transference to the die. A spiral spring 36 connects the fingers 30 with the frame 40 and is extended by the rearward movement of said fingers, said spring reacting and drawing the fingers back to their normal position when the shaft 16 moves rearwardly, and thus permits the arms 32 to return to their normal 45 position. With this return action the rearward fingers of the pairs 30, striking against the rod 26, disengage the latter from its temporary bearings and return it to the slots 28 28, gravity enabling said rod to finally return to 50 its bearings in said slots as the bed 3 assumes the open position. At such time the inking-roller 27 descends upon the die-plate 37, which latter is suitably adjusted and held upon the bed 3. A pinion 38, fast upon the rod 26, at 55 this time bears upon and meshes with a revolving gear 39, that is pivoted at the side of the frame, said gear receiving its rotating motion from a pulley 40, connected thereto and coupled by a pulley-cord 41 with a pulley 42 60 upon the rotating shaft 24. Thus the inking-roller 27 is caused to rotate upon the die-plate 37 and thoroughly and evenly to ink its surface while passing beneath the said inking-roller. 65

The means for wiping the die-plate to clean

its surface from the ink comprise a roller 43, of soft or yielding material, revolvably mounted upon a rod 44, whose opposite ends are passed through vertical slots or ways 45 45 in opposite sides of the frame, said slots being 70 in advance of the slots 28 28.

Pendent from the rod 44, at either end thereof, is a link or other connection 46, supporting a weight 47, which is secured at one end of a link 48, which latter at its opposite end is pivotally connected to the frame, as at 49. It will be understood that pendent connections are provided at the opposite ends of the rod 44 for the purpose of exerting a uniform pressure to hold the wiping-roller 43 against 80 the surface of the die-plate as the latter passes thereunder.

Paper 50, supplied from a roll 51, whose shaft 52 is journaled in opposite supports 53 53, is passed over a roller 54 and thence around the wiping-roller 43 to provide an intermittently-changing wiping-surface therefor. From the roller 43 the paper passes over a roller 55, thence over a drum 56, which is fast to its shaft 57, and to a receiving-roll 58, the 85 ends of whose shaft 59 are journaled in bearings 60 60 in the frame. The drum 56 is provided with a series of longitudinal peripheral surface corrugations 61 to present an enhanced frictional surface to the paper passed thereover. The shaft 57 of said drum is journaled in bearings in opposite bracket formations 62 62, extending from the frame, and there is also rigidly mounted upon said shaft 57 a yoke composed of a rod 63, carrying a pivotal pawl 64, adapted to engage with the corrugations on drum 56, and a pair of arms 65 65, extending right-angularly from the opposite ends of said rod 63 and rigidly mounted upon the shaft 57. A spring 66, extended between a 105 hook 67 on rod 63 and a connection on an arm 62, tensionally holds the pawl 64 in engagement with the paper upon the drum. Also rigid upon shaft 57 is a spur 68, which extends therefrom right-angularly to the arms 65 65 and has at its free end a friction-roller 69, which bears normally against a cushioned surface upon a horizontal arm 70, secured to and extending from a vertically-disposed rod 71. Said rod 71 is passed loosely within the vertical ways or guides 72 73, which latter are secured to the frame, and said rod is provided with a stop 74 to rest upon a cushion 75 at the upper end of the guide 73 to limit its downward movement. 110

The lower end of rod 71 is furnished with a friction-roller which is located in a position to be struck with an upward blow by a lever-arm 105, that is pivoted at 106 in a support 107. The opposite end 76 of said lever is provided with a friction-roller 77 and is located in the path of a cam or beveled projection 78, which extends radially from the periphery of disk 13. Thus with the rotation of disk 13 when the cam 78 meets the lever end 76 the 120 125 130

latter is depressed, while the lever-arm 105 is elevated and strikes against the roller 72, thereby sharply raising the rod 71 and causing the arm 70 to communicate, through the spur 68, a quick partial turn to the yoke-rod 63, carrying the pawl 64, which latter, being in engagement with the corrugated surface of drum 56 and holding the paper fast thereto, turns the said drum abruptly a partial revolution against the tension of a spring 79, that is fastened to the frame at one end and at its other end is connected with a sprocket-chain 80, that passes around a sprocket-wheel 81 upon the shaft 59, and said sprocket-chain being connected with an arm 82, secured upon shaft 57, whereby at the time when said cam 78 performs its function the paper is drawn sharply around roller 43, and as this action is timed to occur when the roller 43 is upon the die-plate the surface of the latter is effectively cleaned.

The stop 74 on rod 71 is provided with a set-screw 83, whereby said stop may be loosened and adjusted at any desired point upon said rod 71 to regulate its degree of movement when struck by the lever-arm 105 and the consequent quantity of wiping-paper to be drawn across the surface of the die-plate.

Fingers 84, extending from the frame, bear against smooth annular ways (not shown) across the corrugated surface of drum 56, extending to near the point where the paper leaves said drum in its course of travel, the purpose of said fingers being to prevent adhesion of the paper to the drum beyond said point.

The shaft 52 of the paper-supply roll is provided with a disk 85, that is fast thereto, and with a pulley 86, loosely mounted thereon, the latter member being driven, as by a pulley-cord 87, from a power-shaft. (Not shown.) A friction-disk 88, as of leather, is placed upon shaft 52 between said pulley 86 and disk 85, and a spiral spring 89 is placed about the shaft intermediate and exerting pressure against said pulley 86 and a stop 90, that is fast upon the shaft, whereby with the rotation of pulley 86 in an opposite direction to the intermittent rotation of shaft 52 a constant tensional friction is set up to prevent unwinding of the paper 50 from roll 51 excepting as and when a quota thereof is drawn away through the superior force as applied intermittently with the aforesaid operation of the feed mechanism.

The sprocket-gear 81 is loose upon shaft 59 of the receiving-roll, but has rigidly connected thereto a pair of disks 91, carrying a pivotal pawl 92, that is in engagement with a ratchet 93 to turn shaft 59 a partial revolution and wind the paper 50 upon roll 58 with the intermittent movement of sprocket 81. A spiral spring 94, intermediate roller 58, and a hub 95 provides, with a friction-disk 96, tensional frictional engaging means between the sprocket 81 and shaft 59 to turn the latter and

wind the paper, while the back revolution of sprocket 81 occurs independently of a corresponding movement of shaft 59, because the pawl 92 is then free from the ratchet 93.

Vertical slots 97 97 are provided in the frame at either side intermediate the slots 28 28 and 45 45, and an idle rod or roller 98, located intermediate the paper-roller 43 and inking-roller 27, is engaged at its opposite ends within said slots 97 97, being adapted to maintain its relative position intermediate the inking and paper rollers under all conditions of elevation thereof by the movement of bed 3 and the curved arms or ways 29 29, thereby preventing the paper from coming in contact with said inking-roller.

Located upon the bed 3 at each side of and in advance of the die-plate in either direction are the adjustable surface projections 99 99, whose function is when the bed 3 is moving to the folded or impressing position to meet the hubs 100 100 upon the inking-roller in advance of the die-plate, and because said projections extend above the bed-surface to a greater extent than the die-plate they cause said roller to be elevated above the die-plate, whereby as the latter follows the said roller falls upon it. The inking-roller thus avoids depositing a large quantity of ink at the edge of the die-plate, and the wiping-roller is enabled to perform its function efficiently in cleaning the entire surface of the plate.

The usual fingers 101 extend from a projection 102 at the pivotal end of bed 3 and are tensionally held apart from the table when the latter is extended open, but said fingers serving to hold the sheet to be printed upon said table as it assumes a vertical position.

Entered in an aperture in the rear of the ink-reservoir 20 at a point near its perimeter is a nozzle 103, from which excess ink may flow to a receptacle 104, whereby the fluid-line in said reservoir is maintained at such level as will avoid liability of the ink as agitated from falling over the sides of the reservoir.

In the operation of my improved machine with the rotation of the fly-wheel 108 its shaft 7, having pinion 8, rotates the gear 9, which transmits the same movement to disk 13 and through the cranks 15 and 17 and links 18 moves the bed 3 and frame 6 from the open extended position shown in Fig. 1 to the closed or folded position shown in Fig. 2. In this movement the rollers 26, 98, and 44 have been raised in their respective slots by the bed 3 and its extensions 29 29, while the shaft 16, striking against the arms 32 32, has deflected the fingers 30 30, carrying the roller 26 with its inking-pad onto the feed inking-roller. In the first stage of this movement, however, the die-plate has passed under the inking-roller 27 and thence beneath the wiping-roller 43, the cam 78 at this latter moment having struck the arm 76, causing the lever 105 to

strike and force upwardly the rod 71, whose arm 70 has jerked upwardly the spur 68, causing the pawl 64 on yoke-rod 63 to suddenly turn the drum 56 and draw a quota of paper across the surface of roller 43, impinging upon the die. This rapid draft of paper occurring while the die is passing beneath the wiping-roller has the effect of very efficiently cleaning the ink from the die-surface, and the subsequent imprint and embossment is performed without disfigurement of the sheet impressed.

Having now described my invention, I declare that what I claim is—

15. 1. In a plate-printing machine, a frame, a bed bearing a die-plate, and a table supporting a sheet to be impressed, together with curved arms or ways extending rearwardly from the bed-surface, an inking-roller, vertical, curved ways or guides in said frame for said roller, an ink-supply at the rear of the machine, and means, when the inking-roller is elevated with the forward movement of the bed, whereby said inking-roller is carried rearwardly to said ink-supply.
20. 2. In a plate-printing machine, the combination with a frame, a bed and a table connected by a common shaft, and actuating mechanism for relatively closing and parting said bed and table with a rocking, oscillatory movement, of curved arms or ways extending rearwardly from the bed-surface, an inking-roller, vertical, curved ways or guides in said frame for said roller, a pair of pivotal, carrier-fingers at each side of the frame, an ink-supply, and means whereby the actuating mechanism causes said fingers to move the inking-roller from its ways or guides to the ink-supply with the forward movement of the bed, and to return it to said ways or guides with the return movement.
25. 3. In a plate-printing machine, the combination with a frame, a bed, a pivotal shaft supporting said bed, a table, a shaft connecting the adjacent ends of said bed and table, and actuating mechanism for relatively closing and parting said bed and table with a rocking, oscillatory movement; of curved arms or ways forming rearward extensions of the bed-surface, an ink-supply, an inking-roller, vertical curved ways or guides in said frame for said roller, a pair of pivotal, carrier-fingers at each side of the frame, a tensional connection between said carrier-fingers and the frame, and opposite extensions for said carrier-fingers located in the forward path of said bed-support shaft, to be moved thereby and rock the carrier-fingers to move the inking-roller to and from the ink-supply.
30. 4. In a plate-printing machine, the combination with a frame, a bed bearing a die-plate, a table supporting a sheet to be impressed, and means for relatively closing and parting said bed and table, of an ink-supply, an inking-roller, guides and carriers upon said frame for

said inking-roller, to, respectively, direct and move the latter between the die-plate and ink-supply, and independent means for rapidly rotating said inking-roller while upon the die-plate.

5. In a plate-printing machine, the combination with a frame, a bed bearing a die-plate, a table supporting a sheet to be impressed, and means for relatively closing and parting said bed and table, of an ink-reservoir, a feed-roller journaled therein, and means for rotating said feed-roller; together with an inking-roller, means for automatically moving the latter to and from the feed-roller, bearings to support said inking-roller while upon the feed-roller, a gear upon said feed-roller, and a pinion upon said inking-roller adapted to mesh with said gear, to rotate the former positively.

6. In a plate-printing machine, the combination with a frame and a bed bearing a die-plate, of an inking-roller, vertical guideways in the frame for said roller, means causing said bed to pass beneath said roller with a rising movement, studs upon said bed at the sides of, and in advance of the die-plate, said studs having a greater elevation than said die-plate, and extensions on the roller adapted to be met by said studs and to raise the inking-roller over the advancing edge of and onto the surface of the die-plate.

7. In a plate-printing machine, the combination with an oscillating bed bearing a die-plate, and means for inking the latter, of a wiping-roller, means for passing said die-plate, under pressure, across the surface of said roller, a strip of wiping-paper intermediate said roller and die-plate; and means, regulated with the transit of the die-plate across the roller, for sharply drawing a quota of said paper about said roller during such transit.

8. In a plate-printing machine, the combination with a frame, an oscillating bed bearing a die-plate, and means for inking the latter, of a wiping-roller comprising a shaft and a soft, concentric pad, rotatable thereon, vertical ways in said frame for said shaft, and means for tensionally depressing said shaft; together with a strip of wiping-paper passed about said pad, and independent means for intermittently sharply changing the paper wiping-surface.

9. In a plate-printing machine, the combination with a frame, an oscillating bed bearing a die-plate, and means for inking the latter, of a wiping-roller comprising a shaft having a soft, concentric pad rotatable thereon, vertical ways in said frame for said shaft, weights pendent at each end of said shaft, pivotal connections between the frame and said weights, to steady the latter, a paper-supply roll, a paper-receiving roll, a paper strip extending from one roll to the other and passed about the wiping-roller, and means for sharply drawing the paper strip intermittently about said wiping-roller.

10. In a plate-printing machine, the combination with a frame and a movable bed bearing a die-plate, of a wiping-roller, vertical ways in the frame therefor, a paper-supply roll, a paper-receiving roll, a strip of wiping-paper passed from one roll to the other, and including the wiping-roller in its course, a feed-drum between said wiping-roller and receiving-roller, a frictional hold and release 10 for the paper upon said drum, and means for quickly moving said drum a partial revolution to draw a quota of paper about said wiping-roller.

11. In a plate-printing machine, an intermittent feed mechanism for wiping-paper to clean a die-plate, a paper-supply roll, a wiping-roller, means for directing the paper thereto, a drum having transverse corrugations, means for directing the paper to said 20 drum, a receiving-roll, a yoke rigid upon the drum-shaft, a pawl upon said yoke engaging with the paper and the drum, a spur extending from the drum-shaft, and mechanism for moving said spur to turn the drum a partial revolution and draw a quota of paper about the wiping-roller.

12. In a plate-printing machine, an intermittent feed mechanism for wiping-paper to clean a die-plate, a paper-supply roll, a wiping-roller, means for directing the paper thereto, a drum having transverse corrugations, means for directing the paper to said drum, a receiving-roll, a yoke rigid upon the drum-shaft, a pawl upon said yoke engaging 30 with the paper and the drum, a spur extending from the drum-shaft, and mechanism for moving said spur to turn the drum a partial revolution and draw a quota of paper about the wiping-roller; together with a receiving- 35 roll, a sprocket-wheel upon the shaft thereof, means to frictionally engage said sprocket-

wheel and roll in one direction, an arm extending from said drum-shaft, and a sprocket-chain about said sprocket-wheel, said chain being connected at one end to said arm and at 45 its other end to a tensional retractile support.

13. In a plate-printing machine, the combination with a frame, die-plate bed, and mechanism, including a rotating member, for operating the bed, of a wiping-roller, a strip of 50 paper passed thereabout, a supply-roll, a receiving-roll, and an intermediate rock member to feed the paper intermittently; together with a vertical rod, an actuating connection between said rock member and said rod, 55 guides upon the frame for said rod, means for adjusting the elevation of said rod, a lever fulcrumed in the frame, a cam upon the rotating member arranged to depress one end of said lever in its rotation, and said lever being arranged to carry upwardly the said vertical rod.

14. In a plate-printing machine, the combination with a frame, a die-plate bed and mechanism for moving the latter, of opposite, vertical, curved slots in the frame to receive an inking-roller, opposite, vertical slots in the frame to receive a wiping-roller, a strip of paper passed about said latter member, said rollers being movable in their respective slots 60 with the bed movement; together with opposite slots in the frame intermediate the aforesaid inking-roller and wiping-roller slots, and an idle rod or roller located in said intermediate slots to separate the paper from the inking- 65 roller.

Signed at New York this 24th day of April, 1903.

WILLIAM S. EATON.
